CAR TRUCK

James A. Shafer, East Cleveland, Ohio, assignor to National Malleable and Steel Castings Company, Cleveland, Ohio, a corporation of Ohio

Application July 16, 1937, Serial No. 153,884

10 Claims. (Cl. 105—197)

This invention relates to car trucks and more particularly embodies certain improvements over the car truck shown in my copending application Ser. No. 109,285, filed November 5, 1936.

In my aforesaid application there is shown a side frame having a window opening and a shelf at the bottom of the opening. The bolster is formed with depending projections extending downwardly through openings in the shelf and resting on springs in the tension member of the side frame. There are also springs on the shelf extending upwardly into pockets in the end of the bolster, which springs are shorter and of greater diameter than the springs in the tension member. Shorter springs are used on the upper level so that there would still be sufficient room between the top of the bolster and compression member above the window opening to raise the bolster, during assembly and disassembly of the truck, an amount sufficient to withdraw the downwardly extending projections entirely out of the openings in the side frame shelf. My present invention concerns an arrangement in which longer springs can be used on the upper level, than can be applied in the construction shown in my copending application, the increased length of springs in no way affecting ready assembly and disassembly of the side frames and bolster. The length of the spring may be increased to such an extent that the same type of springs can be used in the tension member and in the bolster. This arrangement eliminates the necessity of the railroad carrying two different sizes of springs in stock for this particular type of truck.

In the accompanying drawings:

Figure 1 is a view in elevation, showing an embodiment of my invention with a portion of the bolster and side frame in section taken on line 1—1 of Fig. 2.

Figure 2 is a view partly in plan and partly in section, the latter being taken on line 2—2 of Fig. 1.

Figure 3 is a vertical sectional view taken on line 3—3 of Fig. 1.

Figure 4 is a view similar to Fig. 3, but showing the bolster in raised position.

Figure 5 is an elevational view showing a modified form of spring cap; and

Figure 6 is a plan view of the cap shown in Fig. 5.

In the drawings, the side frame 10 is similar to the one shown in my previous application Ser. No. 109,285, and comprises a compression member 11, tension member 12, and vertical connecting columns 13, 13. The tension member 12 com-

prises a horizontal portion 14 of box-section and upwardly sloping channel-shape members 15, 15. A window opening 16 is formed by the tension and compression members and columns and receives an end of the bolster 17. The horizontal portion of the tension member is formed with a bottom wall 18, side walls 19, 19 and a top wall or shelf 20. Sleeves 21, 21 extend downwardly into the tension member from shelf 20 and the shelf is formed with openings in line with the sleeves, as in my previous construction, for receiving the projections 22, 22 extending downwardly from the bolster. Springs 23, 23 extend between the upper surface of bottom wall 18 and under surface of projections 22 to support the bolster.

It will be apparent that the engagement between projections 22 and sleeves 21 limits horizontal movement between the side frame and bolster, and that in order to assemble and disassemble these parts, sufficient clearance must be provided, between the upper wall of the bolster and the under side of compression member 11 directly above the bolster, to permit the projections 22 to be withdrawn from sleeves 21 to a position wherein they are entirely above shelf 20. The present-day standards set by the Association of American Railroads limit the extent to which the compression member can be raised so as to increase the aforementioned clearance. My invention, however, does not contemplate any change in the side frame construction in order to utilize springs in the bolster of the same size as those in the tension member. Referring particularly to Figs. 1, 2 and 3, the top wall 25 of the bolster is formed with openings 26 and 27 which permit the upper springs 28 and 29 to project above the top wall 25. The bolster is operatively engaged with the tops of springs 28 and 29 through spring caps 30, 30, each of which comprises a top wall 31 and a depending cylindrical side wall 32, the latter wall overlapping a considerable portion of each spring so as to position the same in the truck. Projecting outwardly from each wall 32 is an annular flange 33 which engages the under surface of top wall 25 of the bolster immediately adjacent each of the openings 26 and 27, thus, in effect, supporting the bolster thereon. It will be readily apparent that downward movement of the bolster will be resisted by springs 28 and 29 through the spring caps 30.

To disassemble the truck, the bolster is jacked up to the position shown in Fig. 4, leaving the upper springs 28 and 29 resting on shelf 20 with the respective spring caps resting in their same relative position on the springs. In this position

of the bolster the projections 22 are above the level of shelf 20 and after the usual wedges and brasses have been removed from the journal box the side frame may be withdrawn from the end of the bolster. During the latter operation, shelf 20 of the side frame will, in effect, be slid from beneath springs 28 and 29 until the springs either drop out of their respective pockets in the bolster or are removed by hand. While my invention 10 has been described in connection with one side frame and one end of the bolster, it will be understood that a similar side frame co-operates with the other end of the bolster in like manner.

In Figs. 5 and 6 there is shown a construction 15 in which the individual spring caps have been joined by webs 35, 35 so that the two portions 36 and 37 of the caps will function as a unit. With such a construction it would only be necessary to handle one piece instead of the two shown in 20 Figs. 1 to 4. The operation of the truck otherwise would be the same as where individual spring caps are used for the upper springs.

The terms and expressions which I have employed are used as terms of description and not 25 of limitation, and I have no intention, in the use of such terms and expressions, of excluding any equivalents of the features shown and described or portions thereof, but recognize that various 30 modifications are possible within the scope of the invention claimed.

What I claim is:

1. In a car truck including a side frame and a bolster, said side frame comprising tension and compression members and connecting columns 35 forming a central window opening therebetween, spring means on said side frame extending into said window opening, said bolster having a downwardly opening pocket in an end thereof receiving said spring means, the upper end of said 40 spring means being at a higher level than the end of said bolster, and means including said bolster constructed and arranged to permit said end of said bolster to be raised to a position higher than said end of said spring means.

45 2. In a car truck, a side frame comprising tension and compression members and columns joining said members to form an opening therebetween, a bolster having an end projecting into said opening, said bolster having spring receiving pockets therein and apertures in the upper wall thereof, spring means on said side frame beneath said bolster projecting into said pockets and through said apertures in said bolster, and means 50 engaging said spring means and bolster for causing compression of said spring means upon downward movement of said bolster with respect to said side frame.

55 3. In a car truck a side frame comprising tension and compression members and columns 60 joining said members to form an opening therebetween, a bolster having an end projecting into said opening, said bolster having spring receiving pockets therein and apertures in the upper wall thereof, spring means on said side frame beneath 65 said bolster projecting into said pockets and through said apertures in said bolster, and means engaging said spring means and bolster for causing compression of said spring means upon downward movement of said bolster with respect to 70 said side frame, said last-named means being constructed and arranged as to engage said spring means even when said bolster is raised with respect thereto.

75 4. In a car truck, a side frame comprising a tension and compression member, columns con-

necting said members and forming a window opening therewith, a bolster having an end extending into said opening and a downwardly opening pocket in said end, said bolster having an opening in the upper wall thereof, a spring cap having a portion projecting through said opening, spring means resting on said side frame extending into said pocket and engaging said portion of said spring cap, and means on said cap engaging said bolster to effect compression of said 10 spring means upon downward movement of said bolster relative to said side frame.

5 5. In a car truck, a side frame comprising a tension and compression member, columns connecting said members and forming a window 15 opening therewith, a bolster having an end extending into said opening and a downwardly opening pocket in said end, said bolster having an opening in the upper wall thereof, a spring cap having a portion projecting through said 20 opening, spring means resting on said side frame beneath said bolster, extending into said pocket and engaging said portion of said spring cap, and an annular flange projecting outwardly from said cap and adapted to be engaged by said bolster for 25 effecting compression of said spring means upon downward movement of said bolster relative to said side frame.

6. In a car truck, a side frame comprising tension and compression members, columns connecting said members and forming a window opening therewith, a shelf at the bottom of said window having openings therein, spring means in said tension member beneath said shelf, a bolster having an end projecting into said window 35 and having downward projections extending through the opening in said shelf and engaging said spring means, other spring means on said shelf projecting into and through said bolster, and separable means engaging the upper end of 40 said second-named spring means and adapted to co-operate with said bolster for causing compression of said spring means upon downward movement of said bolster relative to said side frame.

7. In a car truck including a bolster and a pair 45 of side frames, each having a shelf, spring means on said shelf for supporting the bolster, and other spring means below said shelf, said bolster having means integral therewith and depending therefrom at each end thereof for engaging said side frames and tying the latter together, said other spring means co-operating with the means depending from the associated end of the bolster for supporting said bolster, said spring means on said shelf extending upwardly beyond the top of 50 said bolster, and means engaging said bolster and said spring means on said shelf for causing compression of the last mentioned spring means upon downward movement of said bolster with respect to 55 said side frame.

8. In a car truck including a bolster and a pair of side frames, each having a shelf, spring means on said shelf for supporting the bolster, and other spring means below said shelf, said bolster having means integral therewith and depending therefrom at each end thereof for engaging said side frames and tying the latter together, said other spring means co-operating with the means depending from the associated end of the 70 bolster for supporting said bolster, said spring means on said shelf being of substantially the same length as the spring means below said shelf, and means enabling said bolster to be raised to a position wherein said side frame tying means 75

is ineffective while the first mentioned spring means remains on said shelf.

9. In a car truck, a side frame comprising tension and compression members and columns joining said members to form an opening therebetween, a bolster having an end projecting into said opening and spring receiving pockets in said end, said bolster having apertures in the upper wall thereof, helical spring means supported by 5 said side frame projecting upwardly into said pockets and through said apertures in said bolster, and means engaging said spring means and bolster for causing compression of said spring means upon downward movement of said bolster 10 with respect to said side frame.

10. In a car truck, a side frame comprising a tension and a compression member, columns connecting said members and forming a window opening therewith, a bolster having a hollow end portion extending into said opening, said bolster having openings in the upper and lower walls thereof, a spring cap having a portion projecting through said opening in said upper wall, helical spring means supported by said side frame extending through the opening in said lower wall 10 into said hollow end portion and engaging said portion of said spring cap, and means on said cap engaging said bolster to effect compression of said spring means. 5

JAMES A. SHAFER. 15
